GRIP OR CLUTCH FOR HOLDING WIRES OR CABLES

William J. Magee, deceased, late of Park Ridge, Ill., by Marie E. Magee, administratrix, Park Ridge, Ill., assignor of one-half to A. G. F. Schuster, Chicago, Ill.

Application June 22, 1935, Serial No. 28,006

5 Claims. (Cl. 24—134)

The invention shown on attached drawing is a wire or cable grip or clamp for holding a wire or cable when it is pulled or stretched.

The object of the invention is to provide a grip or clamp which will, when attached or clamped to a wire or cable, hold it with such firmness that the wire or cable can be stretched to the required tension for the purpose it is to serve, without scarring or otherwise damaging the wire. It is so constructed that it is not an obstruction to joints of the wire or cable being made while it is holding the cable and it can be operated so as to readily release the cable in order to again grip it at another position, or it can be readily removed from the cable by hand.

It is constructed so that the force exerted on the handle or draw bar is greatly increased due to the original arrangement of levers through which the pulling force is conveyed to the clamping jaw which grips the wire or cable.

The construction of the grip is such that the pulling force exerted on the draw bar maintains the continuous alignment of the cable in the jaw and in front of it so that no bend occurs which would result in injuring the cable.

It is so constructed that it may be set in position on a wire or cable by the operator who can then go to a remote position on the ground or at an elevation and apply a pulling force to an attached rope which will cause the grip to more firmly clasp the wire or cable without slipping thereon.

The attached drawing shows a side view of the invention, Fig. 1, and a cross sectional view, Fig. 2. The cross sectional view, Fig. 2, illustrates the construction on the irregular line noted as 1, 2, 3, 4, on Fig. 1.

Fig. 1 side view shows a cable 5 located in one of the two grooves in the lower stationary part 40 of the jaw. There are two grooves 6 and 7 so that one grip will accommodate various sized wires or cables.

The invention includes a body 8 in the lower inner portion of which are located the two grooves 6 and 7. The body is constructed of a metal which will permit of the grooves being so treated during construction that they will be of such hardness as will give reasonable service with a minimum wear. To the upper part of the body 50 is attached a toggle 9 by means of a bearing pin 10. The upper part of the body is so constructed that the top of toggle 9 has a bearing surface which fits the bearing surface of the body provided by a shoulder 8a. The lower end of toggle 9 is pivoted to toggle 11 by means of a

bearing pin 12. The toggles have bearing surfaces which fit each other. These bearing surfaces, indicated at 11a and 9a, are provided by shoulders 11b and 9b on toggles 11 and 9, respectively. The lower end of toggle 11 is pivoted to the movable clamping jaw 13 by means of a pin 14 and it also fits the bearing surface 15 of jaw 13. Compression strains on the pins 10, 12, and 14 are relieved by the bearing surface 15 engaging the lower end of toggle 11, the bearing surface 11a engaging the lower end of toggle 9, the bearing surface 9a engaging the upper end of toggle 11, and the bearing surface of the shoulder 8a engaging the top of the toggle 9. The pin 14 rigidly fits the jaw 13 and is prevented from turning in it by means of the two parallel surfaces 16. The jaw 13 can move in a direction at right angles to the grooved surface in the lower frame 8 by means of the elongated hole surfaces 16 in the body 8. The fit of flat surface 17 of pin 14 in the groove 16 of the body 8 is sufficiently loose so that when the movable clamping jaw is clamped down against a wire or cable, both ends 18 and 19 will press with equal force against the wire or cable. Pivoted to the toggles 9 and 11 by means of pin 12 is the jaw end 21 of draw bar 20. Draw bar 20 is held in position to body 8 by means of a bearing cap 22 which allows the draw bar 20 to move backward and forward which in turn actuates the toggles 9 and 11. On the other end of the draw bar 20 is the circular shaped handle 22 to enable a cable or rope to be passed through and tied to it. Encircling the handle is a spring 23 which is located around the draw bar 20 and between the outside of body 8 and the inner side of the circular handle end 22. The spring 23 is of such length when fully expanded that it will hold the draw bar in such a position that the clamping jaw is pressed down against the wire or cable.

In order to attach the grip to a wire or cable the operator takes hold of the grip by placing the 4 fingers of his hand against the inner surface of the body at the points marked x 24 and by placing the thumb of his hand against the x 25 mark of handle 22. With his hand the operator forces the draw bar forward which actuates the toggles to raise the clamping jaw 13, which permits the operator to insert the wire or cable in the groove 6 or 7. By releasing the pressure on the thumb the movable clamping jaw presses against the wire or cable, which in turn is pressed against the jaw on the body. By means of a rope, wire or cable attached to the circular handle end of the draw bar 20 the operator can go

to a remote position and apply a pulling force or attach the pulling wire rope or cable to a winch for a more forceful pulling of the grip and the wire or cable to which it has been gripped.

5 The grip may be constructed so the number of grooves 6 and 7 may be increased in number to suit various sizes of wires or cables, and the shapes and relative proportion of the various parts of the grip or clamp may be varied to suit 10 economic manufacture and convenience of operation without departing from the substance of the invention.

The claims for this invention are as follows:

1. A clamp of the character described comprising 15 a frame, a jaw thereon, a second jaw facing said first named jaw, means slidably mounting said second jaw on the frame for movement bodily toward and away from the first named jaw, a toggle link pivoted on the frame, and a second 20 toggle link pivoted on said second jaw and pivotally secured to the first named link, guide means at the pivotal connection of said second link and second jaw slidably connected with said frame to guide the second jaw directly toward 25 and away from said first named jaw, and a draw bar connected to said links at a point where they are pivotally secured together and movable in said frame.

2. A cable grip which comprises a frame, a 30 stationary jaw on said frame, a movable jaw mounted on said frame for sliding movement toward and away from said stationary jaw in a direction substantially perpendicular to the stationary jaw, a pair of toggle links pivoted to 35 each other with one pivoted to the frame and the other to the movable jaw whereby movement of said links toward alignment with each other moves said movable jaw toward the stationary jaw, and a draw bar connected to the links at a 40 point where they are pivotally secured together and slidably mounted on the frame, and spring means pressing the bar in a direction to move the jaws together.

3. In a clamp of the character described, a 45 frame, a stationary jaw, a movable jaw slidably mounted on the frame for movement toward and away from the stationary jaw, a toggle link, a pivot pin connecting said link with the movable

jaw, a second toggle link, a pivot pin connecting said links to each other, a pivot pin on the frame spaced from said movable jaw, said second toggle link being mounted on said last named pivot pin, and means to connect the toggle links to a tensioning device whereby to apply cable tensioning force to said links for closing the jaws upon a cable said last named means comprising a draw bar secured to the pivot pin which connects said links together.

4. In a clamp of the character described, a frame, a stationary jaw, a movable jaw slidably mounted on the frame for movement toward and away from the stationary jaw, a toggle link, a pivot pin connecting said link with the movable 15 jaw, a second toggle link, a pivot pin connecting said links to each other, a pivot pin on the frame spaced from said movable jaw, said second toggle link being mounted on said last named pivot pin, and means to connect the toggle links to a tensioning device whereby to apply cable tensioning force to said links for closing the jaws upon a cable, said movable jaw having a bearing surface engaged by the adjacent end of the first named link, each link having a bearing surface engaged 20 by the end of the other link, and the frame having a bearing surface engaged by the adjacent end of the second link.

5. In a clamp of the character described, a frame, a stationary jaw, a movable jaw slidably mounted on the frame for movement toward and away from the stationary jaw, a toggle link, a pivot pin connecting said link with the movable jaw, a second toggle link, a pivot pin connecting said links to each other, a pivot pin on the frame 30 spaced from said movable jaw, said second toggle link being mounted on said last named pivot pin, and means to connect the toggle links to a tensioning device whereby to apply cable tensioning force to said links for closing the jaws upon a 35 cable, said last named means comprising a draw bar mounted on said second named pivot pin, and a bearing on said frame through which said draw bar is slidable.
